United States Patent Office

Des. 233,993
Patented Dec. 24, 1974

233,993

COMBINED CROSS AND PEACE SYMBOL

Marvin L. Hicks, 22 Melville Ave.,
Greenville, S.C. 29605

Original design application Apr. 11, 1973, Ser. No.
349,964. Divided and this application Mar. 27,
1974, Ser. No. 455,313

Term of patent 14 years

Int. Cl. D11—02
U.S. Cl. D29—23 A

FIG. 1

FIG. 2

FIG. 1 is a side elevational view of a combined cross and peace symbol showing my new design; and

FIG. 2 is an edge elevational view.

This is a division of application Ser. No. 349,964, filed Apr. 11, 1973.

I claim:

The ornamental design for a combined cross and peace symbol, substantially as shown.
